(57) **CLAIM**

The ornamental design for a ceiling fan assembly, as shown and described.

DESCRIPTION

FIG. 1 is a top perspective of the ceiling fan assembly, showing my new design.

FIG. 2 is a bottom perspective thereof;

FIG. 3 is an enlarged view of FIG. 2;

FIG. 4 is a top view thereof;

FIG. 5 is a bottom view thereof;

FIG. 6 is a front view thereof;

FIG. 7 is an enlarged view of FIG. 6;

FIG. 8 is a rear view thereof;

FIG. 9 is a right-side view thereof; and,

FIG. 10 is a left-side view thereof.

The broken lines illustrate portions of the ceiling fan assembly and form no part of the claimed design.

The jagged break lines represent broken away symbols and form no part of the claimed design. The appearance of any portion of the ceiling fan assembly between jagged break lines forms no part of the claimed design.

The dot-dash broken lines encircling portions of the ceiling fan assembly indicate enlargement boundaries and form no part of the claimed design.

See application file for complete search history.
